ABSTRACT

High torque multiplication with ready reversibility and absence of surging are obtained by a pair of oppositely toothed circular rotors fixed to a circular separator therebetween and smoothly rotatably fitted in a coaxial cylindrical chamber and fed by high pressure fluid. The combination of such rotor and chamber is utilized in a system including a clutch drive switchably passing fluid through or past such combination of rotors and rotor chamber and in reversible directions; the preferred system is a vehicle.

HYDRAULIC MULTIPLIER VEHICULAR SYSTEM

BACKGROUND OF THE INVENTION:

1. THE FIELD OF THE INVENTION:

The fields of the invention are in power transmission of hydraulic type using rotary fluid and in clutches and power steps controls with means to effect torque reversal.

2. DESCRIPTION OF THE PRIOR ART:

The prior art effected torque multiplication by gear drive rotor selection that theoretically permitted relatively constant speed of a driving motor; however, the gears subjected the motor and/or driving mechanism to impact stresses that were undesirable and/or damaging; hydraulic multipliers were substantially unidirectional and also subject to impact action due to surges and lags in correction time. Both types of structures have involved mechanisms and structures. This invention provides safe, inexpensive, reliable torque multiplication without undesirable side effects of the prior art apparatuses.

BRIEF DESCRIPTION OF THE DRAWINGS:

FIG. 1 is a top plan diagrammatic view of a vehicle 25 equipped according to this invention.

FIG. 2 is an enlarged side and vertical longitudinal sectional view of zone 2A of FIG. 1.

FIG. 3 is a diagrammatic representation of the hydraulic connections of components shown in FIGS. 2 30 and 11 and 8.

FIG. 4 is a side view of the selector assembly 45 when unit 46 is operatively connected to selector assembly input shaft 49 and output shaft 50.

FIG. 5 is an interior longitudinal cross-sectional view 35 of the selector assembly in the position of parts shown in FIG. 4.

FIG. 6 is an interior longitudinal cross-sectional view of the selector assembly 46 in the position of parts thereof wherein the unit 46 is disconnected from the power source 37 and shafts 49 and 50 for power transmission therebetween.

FIG. 7 is a side view of the torque multiplier unit 46 along direction of arrow 7A of FIG. 10.

FIG. 8 is a serially broken away view of unit 46 along planes 8A, 8B, 8C, 8D, 8E, 8F; planes 8A, 8B, 8C and 8D are shown in FIG. 7; planes 8C, 8D and 8E are shown in FIG. 10, planes 8Dm 8E, 8F and 8G are shown in FIG. 9.

FIG. 9 is a side view of the torque multiplier unit 46 along direction of arrow 9A of FIG. 10.

FIG. 10 is a diagrammatic broken-away view through section 10A-10A of the casing of unit 46 to expose the torque multiplier rotor unit which is shown in end view along direction of arrow 10B of FIG. 8.

FIG. 11 is a perspective broken-away view of the torque multiplier unit 46 with casing 90 broken away at section 10A-10A.

DESCRIPTION OF THE PREFERRED EMBODIMENT:

In general, this overall apparatus is a vehicle 20 with a frame 30, a power source 37 and a torque multiplier assembly 43.

The frame 30 is rigid and is composed of, firmly joined together, rigid back member 31, a rigid front member 32, a rigid left side member 33 and a rigid right

side member 34, with transverse rigid cross members 36, 36' and 36''. The frame supports a power source, internal combustion engine 37, and a transmission 41 and a torque multiplier assembly 43. The engine 37 drives transmission output shaft 39 through a standard variable speed transmission 41; transmission 41 operates through a transmission output shaft housing 42. Back right drive wheel 21, back left drive wheel 22, front pivotal left wheel 23 and front pivotal right wheel 24 are attached to the frame 20 in conventional manner and to a steering wheel 27 which is in the vicinity of a driver 35 and supported on the frame 30 steering post 26. The transmission assembly 41 is operatively connected to and powers torque multiplier assembly 43. Assembly 43 has a converter output shaft 50 which is operatively connected to the drive wheels 21 and 22. A driver's seat 25 is firmly yet adjustably supported on frame 30 and driver 35 may sit on seat 25.

The torque multiplier assembly 43 comprises a 20 torque multiplier drive selector assembly 45, a torque multiplier unit 46 and a torque multiplier control assembly 47 therefor in co-operative combination and firmly attached to frame 30.

The selector assembly 45, the parts of which are shown in FIGS. 4-6, comprises, in co-operative connection,

- static members such as a rigid casing 51 and the journal bearings 72 and 82,
- axially rotatable members which are longitudinally fixed, such as the rigid cylindrical converter input shaft 49 and the rigid cylindrical converter output shaft 50 which are rotatably supported in the journal bearings 72 and 82 and sleeve 61; and wheels 60 and 68,
- longitudinally movable non-rotating members as fork unit 52, and
- longitudinally and rotatably moving members as sprockets 63 and 71' and sleeve unit 67.

Output shaft 39 of transmission 41 is firmly attached to input shaft 49 as by a key 28 in a collar 29.

Casing 51 is firmly fixed to a cross member 36 of frame 30 and to the transmission 41; a torque multiplier casing 48 is also firmly attached to transmission 41 and another cross member 36'' of the frame 30.

Motor 37 and transmission 41 are also firmly attached to frame 30.

The group of axially rotatable members includes driven output circular gear wheel 60 and driving input drive gear wheel 68. Gear wheels 60 and 68 are co-axial with shafts 50 and 49 respectively and shafts 50 and 49 are co-axial. The driven output gear wheel 60 is rotatably supported in fixed longitudinal position on the shaft 50 and the input gear drive wheel 68 is rotatably supported in fixed longitudinal position on the input shaft 49. Collars 60' and 68' each have set screws 60S and 68S respectively that are firmly seated therein and slidably extend into circular slots 50S and 49S respectively thereon on shafts 50 and 49 respectively. Also, each of the collars 60' and 68' is fixed to the wheels 60 and 61 respectively and locate those wheels in their longitudinal position on shafts 50 and 49 respectively thereby permitting those wheels to rotate about those shafts, respectively.

Shaft 50 is provided with an axially or longitudinally extending set of rigid output splines 73 and axially or longitudinally extending set of rigid bypass splines 75; the shaft 49 is provided with longitudinally extending

sets of rigid longitudinally extending bypass splines 79 and input splines 80. Splines of sets 73, 75, 79 and 80 extend radially from their shafts and are the same in size and shape. The set of bypass splines 75 of shaft 50 are located at the right-hand (as shown in FIG. 5) end of the shaft 50, while the set of output splines 73 of output shaft 50 are located spaced leftwardly away therefrom and near the output gear wheel 60, as shown in FIGS. 4 and 5. The set of input splines 80 of the input shaft are located on the right-hand side of the input shaft, as shown in FIG. 5, while the set of bypass splines 79 of the input shaft 49 are located toward the output end 77 of the input shaft (to the left, as shown in FIGS. 5 and 6).

The gear wheels 60 and 68 are driven by the drive plates 61 and 69 respectively when the teeth 132 and 134 of those drive plates are moved by the fork unit 52 into engagement with the teeth as 131 and 133 of the wheels 60 and 68 respectively.

The wheels 60 and 68 respectively are operatively connected to power transmission elements as drive chains 123 and 121 respectively, which chains are operatively connected to torque multiplier unit output gear wheel 128 and torque multiplier unit input gear wheel 126, respectively.

A rigid longitudinally movable non-rotating fork unit 52 extends longitudinally of and is slidably attached to the casing 51. Fork unit 52 comprises

- a. a rigid longitudinal spacing bar 56; bar 56 has firmly attached to its left end thereof (as in FIGS. 4-6),
- b. an output yoke 53, and,
- c. at the middle thereof, a sleeve control yoke 54, and
- d. at the right end thereof, as shown in FIGS. 4-6, an input yoke 55, and
- e. a control handle 84.

The longitudinally movable non-rotating fork unit 52 is slidably supported in the brackets 85, 86, 87 and 88 on the rigid casing ceiling 81 for longitudinal movement along the length of the casing. Control handle 84 is firmly fixed to the bar 56 and extends upward through a slot 83 in ceiling 81 of casing 51. Handle 84 is operatively connected to an operator's control handle 145 through a selector control linkage 146.

The control sleeve unit 67 and sprockets 62 and 63 comprise the large longitudinally movable and also rotatable elements of the assembly 45 and are co-axial with the shafts 49 and 50 and rotatably supported thereon and movable therealong and are cooperatively connected with those shafts and the splines thereof.

The control sleeve unit 67 is a hollow rigid cylindrical sleeve comprising a rigid cylindrical longitudinally extending side wall 64C and end walls 64A and 64B and interior sleeve spline sets 74 and 78. More particularly, a set of longitudinally extending sleeve output splines 74 and a like input sleeve spline set 78 are rigidly fixed to the interior of the cylindrical wall 64C and extend inwardly thereof. The splines of set 74 match with the splines of sets 75 and the splines of set 78 match with the splines of set 79; by "match" is meant having equal number and size (as measured in transverse section).

Circular flanges 65 and 66 fixed to the outside wall 64C slidably engage fork arm 58 to provide for movement of sleeve unit 67 lengthwise of casing 51.

The output sprocket 73 comprises a rigid collar 62 and a toothed drive plate 61 and a flange 62A firmly

joined together. The rigid cylindrical collar 62 is internally grooved to match and accept the splines of the shaft output spline set 73 and is firmly fixed to a toothed circular output drive plate 61. A circular flange 62A extends radially from the periphery of the sprocket body 62 and slidably yet firmly engages the arms 57 of the yoke 53 whereby the yoke arm 53, sprocket body 62 and the drive plate 61 move longitudinally of the shaft 50, together with the remainder of the fork unit 52. The drive plate 61 is a rigid circular plate co-axial with shaft 50 and is provided with a plurality of equi-sized clutch teeth 132 that extend parallel to axis of shaft 50, and in position of parts shown in FIGS. 4 and 5, engage with equally sized and spaced teeth clutch teeth 131 on gear wheel 60. A multiplier output continuous drive chain 123 engages the teeth 136 on drive wheel 60.

The input sprocket 71' comprises a collar 71, a flange 70 and a toothed drive plate 69. The collar 71 is a rigid cylindrical body internally grooved to match and accept the splines of input spline set 80. The splines 80 (like 73) slidably engage such grooves in input sprocket body 71 (as in sprocket body 62). A circular input sprocket flange 70 extends radially from and is firmly fixed to the periphery of the sprocket body 71 and slidably engages arm 59 of yoke 55 whereby arm 55, sprocket body 71 and plate 69 move longitudinally of shaft 49 together with remainder of the fork unit 52 and other units as 67 and 73 moving therewith.

The output end of the body 71 is firmly fixed to a rigid circular toothed drive sprocket plate 69 co-axial with shaft 49. The sprocket plate 69 is provided with clutch teeth 134 equal in size and spacing that extend parallel to axis of shaft 49 (and 50) and, in position of FIGS. 4 and 5, engage equally sized and spaced clutch teeth 133 on drive gear wheel 68.

A multiplier input continuous chain 121 engages teeth 138 on drive gear wheel 68.

The right-hand (as shown in FIGS. 4-6) input end of shaft 50 has a rigid cylindrical cap 76 that has a smooth sliding fit with interior of sleeve 64C and a smooth sliding fit on output end 77 of shaft 49.

Also, the arm 54 is provided with adjustable lock nuts 54A and 54B to locate roof 81 in fixed spatial relationship to the yoke 58 (which may be a bearing) and shafts 49 and 50, especially as the casing 51 is sufficiently rigid to be dimensionally stable during operation of the assembly 43. Accordingly, shafts 49 and 50 are held co-axial during operation of the assembly 43 by sleeve unit 67 and journal bearings 72 and 82 and casing 51.

When it is desired to utilize the force multiplication of the unit 46, the handle 84 of fork unit 52 is moved (leftwards as shown in FIGS. 4-6) away from input end, 49A, of the shaft 49. This movement of unit 52 and its arm 54 moves the yoke arms 58, 57 and 59 of the arms 54, 53 and 55, respectively, (to the left, as shown in FIGS. 4-6); on such movement of unit 52, the yoke arm 58 engages the flanges 65 and 66 on the cylindrical body 64 of the sleeve 67 and the sleeve unit 67 is thereby moved longitudinally (to the left) while still allowed to rotate about the axis of the shafts 49 and 50. In such position, as shown in FIG. 5, the teeth 131 and 132 of the driven sprocket 60 and the sprocket body 63 are engaged while the teeth 133 and 134 of the plate 68 and 69, respectively, are also together and engaged with each other. In this stage of operation, there

is power transmission through the gear wheels 68 and 60, via drive chains 121 and 123, to and from the unit 46. Accordingly, manipulation of the fork unit handle 84 provides for selective connection of transmission of power from the shaft 49 to the unit 46 to shaft 50 in the position of parts shown in FIG. 5.

In operation of the selector assembly 45 in the position of parts shown in FIGS. 4 and 5, with the control handle 84 moved to the right-hand (input) side of the shaft 49 of the slot 83 in the casing 51, power is transmitted from shaft 49 to the sprocket body 71 through the teeth 134 to the teeth 133 through the drive wheel 68 through the input or drive chain 121 to the unit 46. The multiplier output chain 123 transfers power from unit 46 to the drive sprocket gear wheel 60 which is, (except for its attachment to sprocket 63 freely rotatable about the shaft 50) and from such sprocket wheel 60 through its teeth 131 of the plate 60 to the teeth 132 of the plate 61 to sprocket body 62 and therefrom to the splines 73 on the shaft 50.

In this position of parts, shown in FIGS. 4 and 5, the output spline set 74 of sleeve 67 is moved by fork unit 52 from position thereof in FIG. 6 and is disengaged from the bypass spline set 75 on the shaft 50. Similarly, in such position shown in FIG. 5, which condition also exists in the position of parts shown in FIG. 4, the input spline set 78 (the spline members of which set are firmly attached to the interior of the shell 64 and are firmly attached to such rigid shell) are disengaged from the set of bypass splines 79, which spline set is attached to the output end of the shaft 49.

When it is not desired to utilize the force multiplication of the unit 46, the handle 84 of fork unit 52 is moved (rightwards as shown in FIGS. 4-6) toward the input end, 49A, of the shaft 49. This movement of unit 52 and its arm 54 moves the yoke arms 58, 57 and 59 of the arms 54, 53 and 55, respectively, to the right, as shown in FIGS. 4-6; on such movement of unit 52 the yoke arm 58 engages the flanges 65 and 66 on the cylindrical body 64 of the sleeve 67 and the sleeve unit 67 is thereby moved longitudinally to the right and locked to the splines of the shafts 49 and 50. In such position, as shown in FIG. 6, the teeth 131 and 132 of the driven sprocket 60 and the sprocket body 63 are disengaged while the teeth 133 and 134 of the plate 68 and 69, respectively, are also moved apart and disengaged from each other. At this stage of operation (shown in FIG. 6), the sets of splines 74 and 75 are operatively engaged and the sets of splines 78 and 79 are operatively engaged whereby power passes from the shaft 49 through the set of splines 79 to the shell 64C to the splines of set 75, affixed to the shaft 50, and through shaft 50 to the output end of the shaft 50.

In this operation, there is a disengaging of power transmission through the gear wheels 68 and 60 via the chain drive 121 and 123 to the unit 46. Accordingly, manipulation of the fork unit handle 84 provides for selective disconnection of transmission of power from the shaft 49 to the unit 46 in the position of part shown in FIG. 6 and then provides for direct transmission of power from input shaft 49 to output shaft 50.

In operation of the selector assembly 45 in the position of parts shown in FIG. 6, with the control handle 84 moved to the right (input) side of the shaft 49 and of the slot 83 in the casing 51, power is transmitted from shaft 49 past the sprocket body 71 and the teeth 134 and the teeth 133 of the drive wheel 68 and past

but not through the input or drive chain 121 to the unit 46. The multiplier output chain 123 then transfers no power from unit 46 to the driven sprocket gear wheel 60 or teeth 131 and the teeth 132 of the plate 61 to sprocket body 62 and therefrom to the splines 73 on the shaft 50.

In this position of parts, shown in FIG. 6, the output spline set 74 of sleeve 67 is moved by fork unit 52 from position thereof in FIGS. 4 and 5 and is engaged with 10 the bypass spline set 75 on the shaft 50. Similarly, in such position shown in FIG. 6, the input spline set 78 is engaged with the set of bypass splines 79, which spline set is attached to the output end of the shaft 49.

15 The torque multiplier unit 46 comprises a rigid rotor casing 90, a rotor 89, shaft 99, and gears 106 and 107. The casing comprises an upper chamber wall 91, a lower chamber wall 97, both of which are rigid and imperforate, and a cylindrical side wall 98 with the walls 91, 97 and 98 firmly joined together to enclose a rotor chamber 100.

20 The rotor 89 comprises a rigid flat cylindrical top rotor wall 92, a top rigid counter-clockwise toothed body 93, an intermediate rigid flat cylindrical rotor wall 94, a bottom rigid clockwise toothed body 95 and a bottom flat cylindrical rotor wall 96. The elements 92-96 and shaft 99 therefor are all firmly joined together as by screws 109, 109' and 109''. The walls 92, 94 and 96 are flat thin rigid disks of the same thickness 30 and diameter with an exterior diameter forming a close fit to the interior of the circular cylindrical wall 98. A free sliding fit is provided between the adjacent flat surfaces of rotor wall 92 and casing wall 91, and between adjacent flat surfaces of walls 96 and 97. Walls 92, 94 and 96 are generally imperforate.

35 Shaft 99 is rotatably supported in journals 118 and 119 and drives a right angle bevel gear 106; gear 106 engages bevel gear 107; gear 107 drives output shaft 108; shaft 108 and gear 107 are rotatably supported in 40 gear casing 117. Gear casing 117 is firmly fixed to outside of rotor casing 90.

45 Shell 48 of assembly 48 is a rigid cup-shaped casing with bottom wall 156, rear wall 157, front wall 158 and side walls which enclose and surround a chamber 159 wherein are located the rotor assembly 46, brackets as 151-153 and gears 126 and 128. Bracket 151 supports gear casing 117. Bracket 152 supports, on a journal bearing 152', output shaft 108; bracket 153 supports a journal bearing 155 for shafts 108 and 129; brackets 50 154 and 154' support housing of hydraulic pump 122. Shaft 108 is operatively connected to and drives output gear wheel 128; wheel 128 engages chain 123. Gear wheel shaft 129 is supported in journals 155 and 155' and is driven by gear wheel 126 and drives the rotor of 55 hydraulic pump 122. Pump 122 is connected by output line 149 through valve casing 148 and valve body 142 and input lines 101 or 111 to rotor casing 90; rotor discharge lines 105 and 115 are operatively connected to valve casing 148 of reversing valve 150 and therethrough to discharge line 130 which leads to hydraulic sump 141. Sump 141 is connected by hydraulic inlet line 139 to inlet of pump 122. An adjustable relief valve 140 is operatively connected across outlet line 149 to discharge line 130.

60 An inlet line 101 passes through a rigid transition body 102 firmly affixed to the chamber side wall 98 of rotor casing 90 and has a conduit therethrough 103

which enters into rotor chamber 100 located between the walls 91, 96 and 98. A second inlet line 111 is operatively joined to a transition piece 112 which is firmly joined to the chamber wall 98. The transition piece 112 has a conduit 113 continuous with both the passage within line 111 and rotor chamber 100. Conduit 103 and conduit 113 each enter chamber 100 tangent to the portion of the chamber 100 wherein toothed bodies 93 and 95 respectively are located, as shown in FIGS. 7, 8 and 9 and parallel to those bodies.

A top counterclockwise outlet line 105 is joined to an outlet transition piece body 104 which has a conduit therein which is at the same level as and parallel to the top counterclockwise toothed rotor body 93. A bottom clockwise outlet line 115 is operatively joined to the transition body 114 (which body 114 is a mirror image of the transition piece 112) and which has its opening into the chamber 100 at the same level as and parallel to the body of the bottom, clockwise toothed rotor 95. Conduits 105 and 115 leave chamber 100 tangent to the portion of chamber 100 wherein the toothed bodies 93 and 95, respectively, are located. The point of entry of conduit 103 and exit of conduit 115 are, at the same relative radial position as are the same points of conduits 113 and 105, as shown in FIGS. 7-11.

The control assembly 47 is actuated by a conventional car or tractor electric storage automotive battery 40 and, through a switch 44, supported on frame 30, actuates either of valve pilots 143 or 144 to move the valve body 142 to direct hydraulic fluid under pressure from pump 122 to rotor casing 90 to drive the rotor 89 either clockwise or counterclockwise, as seen from above in FIG. 8. Valve 150 may be hand actuated.

The switch 44 and bell crank 145 are located on vehicle 20 in the immediate vicinity of the driver seat 25 and wheel 27 so that the driver may also manipulate the switch 44 and/or crank 145. Bell cranks 145 and 146 are pivotally yet firmly supported on frame 30 as are rotor casing 90 and selector assembly casing 51. Shell 48 is firmly attached to casing of transmission 41 and a cross member as 36' while selector casing 51 is firmly attached to the frame 30.

The rotor casing 90 is in part supported on shell 48 but may be made sufficiently large to have separate attachment to cross member 36' or other members of frame 30. The valve 150 is firmly supported on frame 30 or on rotor casing 90, as shown in FIGS. 2 and 11.

Manipulation of fork handle 84 is accordingly effected by an operator as 35 on seat 25 through a control handle as 145 through a link train, as rigid bell crank 145 pivotally supported on frame 30 and pivotally connected to one end of a rigid link arm 148, its other end in turn pivotally connected to one end of a rigid bell crank 146 pivotally supported on frame 30 and pivotally connected at its other end to one end of a rigid link arm 147, the other end of which is pivotally connected to fork unit handle 84. Handle 84 is slidably located by flanged locking members as 54A and 54B and rod 56 to move along the length of casing 51 but not transversely to such length. Handle 84 may be hand actuated directly.

Accordingly, the driver 25 may pass mechanical power from engine as 37 directly to shaft 50 in the position of parts of selector assembly 45 shown in FIG. 6; alternatively, the driver may pass engine power to the torque multiplier unit 46 by manipulating the fork unit

52, as by control assembly 47, to provide the array of components of the selector assembly shown in FIGS. 4 and 5, and thereby, as above described, pass power from engine 37 via drive wheel 68 to torque multiplier unit 46. The torque multiplier unit 46 because of the much greater distance of

- a. the center of areas over which the force of the hydraulic power of the high pressure hydraulic fluid of pump 122 is applied, as area 124 of tooth 129 of toothed body 93, from the center of rotation of that body, as shaft 99 (in journal bearings 118 and 119) than
- b. the lesser distance of the center of shaft 99 to the center of area of contact of gears 106 and 107, provides a greatly increased output torque at shaft 108. Such output torque is far greater than the input torque provided at shaft 129 (which is firmly connected to driver gear wheel 126 to drive pump 122) or shaft 49. Such increased torque is provided by shaft 108 to drive gear wheel 128, which is firmly attached to shaft 108, a rigid strong shaft, and passed by the continuous chain 123 to gear wheel 60 and, in position of parts shown in FIGS. 4 and 5, as above described, to output shaft 50. For a large conventional tractor of 250 horse power output the internal diameter of rotor casing 90 would be 3 to 4 feet while the center line of contact of bevel gears 106 and 107 would be only from 1 to 3 inches, and usually 1½ inch. The fit of each of the toothed bodies 93 and 95 in walls 92, 94, 96 could be -0.002 inch or as high as -0.010 inch if made, for instance, by rip saw blades or like uniformly cusped or cupped peripheral cut out zones, as 127, or depth 5 to 10 percent of the radius of the rotor case internal diameter. Such spacing (of 0.002 to 0.010 inch) permits avoidance of impact shocks because such structure permits escape or "bleeding" of high pressure liquid through such spacings when a mechanical block is met and so avoids undue strain on the wheel drive axles, as 120 and 125 (respectively operatively joined to wheels 22 and 21). Bodies 93 and 95 are identical in size and similar in shape but are oppositely turned mirror images, as shown in FIGS. 8 and 11, as the teeth as 127 and 127' are oppositely directed on bodies 93 and 95.

Each of the toothed bodies 93 and 95 is a rigid circular metal body coaxial about shaft 99, each with a plurality of like cutaway zones, as 127, at the periphery thereof, much as in the shape of a circular ripsaw. Each zone as 127 has a concave surface, as 124, concave in direction from which fluid is applied thereagainst, as by flow from orifice 103 of conduit 101, in case of body 93, and from orifice 113 of conduit 111 in case of body 95; each such tooth, as 129, is convex on the opposite side, as 110. The term concave does not mean only curvedly shaped, but includes

- a. an acute angled hollow corner, as 164 (FIG. 11) and 164' and the adjacent straight edges, as 163 and 165'; and
- b. an obtuse angled hollow corner, as 162 or 162' and the adjacent straight edges, as 167' and 163 (FIG. 8).

Each body, as 93, includes vanes, as 129, and a central portion 93' to which the vanes and shaft 99 are firmly attached. The term concave as herein used does not mean only curvedly shaped but includes an obtuse

solid corner, as 166 or 166' and the adjacent straight edges, as 165 and 167. For each of the vanes or teeth, as 129 and 129', a line 168 and 170' (FIG. 8) halfway between the front or leading convex edge 110 or 167 and the rear or trailing concave edge, as 124 or 165', that is at an acute angle 171 to the radius, 169, connecting the edge of the tooth to the center of rotation, as center of shaft 99, of the vaned body 93; the angle 171 extends to the side of the radius distant from the source of fluid applied against the vane, as fluid from line 101 against vanes as 129 of body 93 and, for angle 171', fluid from line 111 against vanes as 129' of vaned or toothed body 95.

Such shape provides that when the pressure in chamber 100 does rise to a degree indicating a full stoppage is met, the overflow from one point as 160 at teeth of body 93 is smoothed out by the surfaces as 161 of the teeth on the other toothed body, as 95, whereby surges are eliminated and, when the obstacle is passed, or greater power applied by motor 37 to chain 121, a smooth return to a driving operation by the action of the hydraulic liquid 160' on the concave surfaces facing such fluid stream is accomplished without any further surge and resulting harmful impact. The thickness of the body 93 (like 95) would be one-eighth to 1 inch, plates 92, 94 and 96 also one-eighth to one-fourth inch for a 3 foot internal diameter rotor casing 90. For smaller machines, a rotor casing of 8 inch internal diameter, one-eighth to one-fourth inch thick bodies 93 and 95, plates 92, 94, 96 of one-sixteenth to one-eighth in. thick, and rubber belts and sheaves instead of chain and gear wheels are used.

This structure 46 thus avoids the problem of surging met with conventional relief valves as 140 which have definite pressure differentials between (a) pressure for such valve to close after being opened and (b) pressure to open after being closed, with resulting surging action.

With this apparatus and system, the operator may also, by manipulation of control assembly 47 move valves body 148 to change flow of fluid, as 160'

- a. from pump 122 to rotor chamber 100 to drive the rotor 90 counterclockwise, i.e., providing flow from pump 122 via line 101 into chamber 100 and then driving fluid along conduit 101 and against teeth or vanes 129 to drive rotor 89 counterclockwise and thence via line 105 to sump 141 to
- b. from pump 122 to valve 150 to line 111, to drive rotor 89 clockwise and return fluid via line 115 to valve 150 and sump 141, as shown in FIG. 3. The same high torque is obtained with lack of surging as described above for the operation of rotor 89 counterclockwise.

Gears 106 and 107 may be helical or hypoid although, for purpose of illustration, are shown as straight toothed bevel gears.

The apparatus 43 comprising clutch assembly 45, selector assembly 46 and control assembly 47 may be used to transmit power from a motor to an irrigation pump, the motor being attached to shaft 49, the drive of the output shaft 50 of assembly 43 being attached to the drive shaft of the pump, as, but not limited to, in U.S. Pat. No. 3,335,791.

The fluid 160' is preferably a conventional hydraulic liquid transmission fluid as used in automobile hydraulic transmissions and hydraulic power systems. However, the use of gases, as well as liquids as a power

transmission means is intended to drive the rotor 89. A fit of -0.002 or -0.010 inch means a spacing of 0.002 and 0.010 inch, respectively.

I claim:

1. A vehicular apparatus comprising a frame, a power source and drive wheels, said power source supported on said frame, a power source output shaft operatively connected to said power source, said frame in part supported on said drive wheels, and a first power transmission and a wheel drive shaft between said wheels and said power source and operatively connected thereto, and a torque multiplier assembly, said torque multiplier assembly having a torque multiplier assembly input shaft and a torque multiplier assembly output shaft, said torque multiplier assembly input shaft operatively connected to said transmission means, said transmission means having an input shaft operatively connected to said power source output shaft, said torque multiplier assembly output shaft operatively connected to said wheel drive shaft,

said torque multiplier assembly comprising, in operative combination,

- 1. a selective transmission assembly with an input and output shaft;
- 2. a torque multiplier unit with an input shaft and an output shaft; and
- 3. a selector control assembly, first power transmission means between said selective transmission assembly input shaft and said torque multiplier unit input shaft and operatively connected to said torque multiplier unit input shaft and to said selective transmission assembly input shaft, and second power transmission means between said selective transmission assembly output shaft and said torque multiplier unit and operatively connected to said torque multiplier unit output shaft and to said selective transmission assembly output shaft,

said selector control assembly comprising a movable control means operatively connected to said selective transmission assembly,

said selective transmission assembly first input shaft means operatively connected to said power source, and said selector control means operatively connected to said first and second power transmission means between said torque multiplier input and output shafts and to said selective transmission assembly input and output shafts and movable into either of two positions alternatively operatively connecting said input shaft of said selective transmission assembly directly to the selective transmission assembly output shaft or to said torque multiplier unit input shaft,

said torque multiplier unit comprising a fixed rigid rotor casing and a rotor chamber within said rotor casing and a rotor assembly rotatably supported in said chamber in said rotor casing,

said casing having a cylindrical interior surface, said rotor assembly comprising a first vaned rotor body having concave radial pockets each with concavity directed in one tangential direction, and each of said pockets having a convex pocket wall with convexity directed in a second tangential direction opposite to said one tangential direction, a second rotor body having concave radial pockets directed in an opposite direction to said one tangential direction and having a concavity directed

opposite to said one tangential direction and each of said pockets on said second rotor body having a convex pocket wall with convexity directed parallel to said one tangential direction,
 5 said first and second rotors mounted on a common rotor shaft, said rotor shaft rotatably mounted in said rotor casing and firmly fixed to each of said rotor bodies and to a separator between said first and second rotors, the outer edge of said separator being in loose sliding contact with the interior of 10 said casing, said separator being a solid flat rigid disc,
 the separator having an outer edge closer to said interior casing surface than the radial edges of the rotors;
 each of said rotor bodies comprising a rigid central flat portion and a plurality of like rigid vanes, each vane firmly attached to said central portion and extending radially therefrom and directed radially 20 and tangentially thereto, each vane having a convex front edge and a concave trailing edge, with pockets defined by the front edges and trailing edges of adjacent vanes on the same rotor, each of said pockets open at the radial edges of said rotor vanes, the front and rear edges of each vane rotor 25 body extending in a direction at the same angle to a line tangent to the radial edges of said vane, the edges of each vane on the second rotor body extending at an angle to a line tangent to the radial edges of said vane opposite in direction to the 30 direction of extension of the vanes on the first rotor, and power transmission means attached to and extending between said rotor shaft and said torque multiplier assembly output shaft drive means and operatively connecting them,
 35 said torque multiplier unit having a hydraulic pump means comprising a power input means, a hydraulic input line and a hydraulic output line, said hydraulic output line being operatively connected via a plurality of hydraulic conduit lines to said rotor 40 chamber, one of said hydraulic conduit lines leading into said rotor chamber in a path directed in a first direction at the vanes of one rotor body and another of said conduit lines connected to said rotor chamber in a path directed in an opposite direction to said first direction at the vanes of the 45 second rotor body,
 and hydraulic discharge lines from said rotor chamber to a hydraulic sump chamber, and a hydraulic conduit line from said hydraulic sump to the inlet of said hydraulic pump,
 50 and said first power transmission means from said selective transmission assembly input shaft operatively connecting to the power input means for said pump and the fit of said rotors in said casing chamber has a spacing therebetween of 0.002 to 0.010 inch whereby, when pressure in said rotor chamber rises to a predetermined degree, hydraulic liquid flows over concave vane surfaces to and between 55 said rotor and said casing to convex vane surfaces on the second rotor.

2. Apparatus as in claim 1 wherein said rotor casing has opposing parallel flat side walls and a cylindrical end wall enclosing a rotor chamber, said rotor assembly 60 in said chamber and including a second flat separator disk between one rotor body and one adjacent rotor casing side wall and a third flat separator disk between

another rotor body and an adjacent rotor casing side wall opposite to said first side wall, said second and third separators each having an outer edge closer to the cylindrical interior casing surface than the radial edges 5 of the rotor bodies.

3. Apparatus as in claim 2 wherein all the vaned pockets in one rotor are of the same shape and size.

4. Apparatus as in claim 3 wherein all the vanes and pockets in the second rotor are of the same shape and size on that rotor.

5. Apparatus as in claim 4 wherein the vanes and pockets on both the first and second rotors are of the same shape and size.

6. A torque multiplier assembly comprising, in operative combination,

1. a selective transmission assembly with an input and output shaft;
 2. a torque multiplier unit with an input shaft and an output shaft; and
 3. a selector control assembly, first power transmission means between said selective transmission assembly input shaft and said torque multiplier unit input shaft and operatively connected to said torque multiplier unit input shaft and to said selective transmission assembly input shaft, and second power transmission means between said selective transmission assembly output shaft and said torque multiplier unit and operatively connected to said torque multiplier unit output shaft and to said selective transmission assembly output shaft,
 said selector control assembly comprising a movable control means operatively connected to said selective transmission assembly,

said selective transmission assembly first input shaft means operatively connected to said power source, and said selector control means operatively connected to said first and second power transmission means between said torque multiplier input and output shafts and to said selective transmission assembly input and output shafts and movable into either of two positions alternatively operatively connecting said input shaft of said selective transmission assembly directly to the selective transmission assembly output shaft or to said torque multiplier unit input shaft, said torque multiplier unit comprising a fixed rigid rotor casing and a rotor chamber within said rotor casing and a rotor assembly rotatably supported in said chamber in

said casing having a cylindrical interior surface, said rotor assembly comprising a first vaned rotor body having concave radial pockets each with concavity directed in one tangential direction, and each of said pockets having a convex pocket wall with convexity directed in a second tangential direction opposite to said one tangential direction,

a second rotor body having concave radial pockets directed in an opposite direction to said one tangential direction and having a concavity directed opposite to said one tangential direction and each of said pockets on said second rotor body having a convex pocket wall with convexity directed parallel to said one tangential direction, said first and second rotors mounted on a common rotor shaft, said rotor shaft rotatably mounted in said rotor casing and firmly fixed to each of said

rotor bodies and to a separator between said first and second rotors, the outer edge of said separator being in loose sliding contact with the interior of said casing, said separator being a solid flat rigid disc,
5 the separator having an outer edge closer to said interior casing surface than the radial edges of the rotors;
each of said rotor bodies comprising a rigid central flat portion and a plurality of like rigid vanes, 10 each vane firmly attached to said central portion and extending radially therefrom and directed radially and tangentially thereto, each vane having a convex front edge and a concave trailing edge; with pockets defined by the front edges and 15 trailing edges of adjacent vanes on the same rotor, each of said pockets open at the radial edges of said rotor vanes, the front and rear edges of each vane rotor body extending in a direction at the same angle to a line tangent to the radial edges of said vane, the edges of each vane on the second rotor body extending at an angle to a line tangent to the radial edges of said vane opposite in direction to the direction of extension of the vanes on the first rotor, and power transmission means attached to and extending between said rotor shaft and said torque multiplier assembly 20 output shaft drive means and operatively connecting them,
said torque multiplier unit having a hydraulic pump means comprising a power input means, a hydraulic input line and a hydraulic output line, said hydraulic output line being operatively connected via a plurality of hydraulic conduit lines to said rotor chamber, one of said hydraulic conduit lines leading into said rotor chamber in a path directed in a first direction at the vanes of one rotor body and another of said conduit lines

connected to said rotor chamber in a path directed in an opposite direction to said first direction at the vanes of the second rotor body, and hydraulic discharge lines from said rotor chamber to a hydraulic sump chamber, and a hydraulic conduit line from said hydraulic sump to the inlet of said hydraulic pump, and said first power transmission means from said selective transmission assembly input shaft operatively connecting to the power input means for said pump and the fit of said rotors in said casing chamber has a spacing therebetween of 0.002 to 0.010 inch whereby, when pressure in said rotor chamber rises to a predetermined degree, hydraulic liquid flows over concave vane surfaces to and between said rotor and said casing to convex vane surfaces on the second rotor.

7. Apparatus as in claim 6 wherein said rotor casing has opposing parallel flat side walls and a cylindrical end wall enclosing a rotor chamber, said rotor assembly 25 in said chamber and including a second flat separator disk between one rotor body and one adjacent rotor casing side wall and a third flat separator disk between another rotor body and an adjacent rotor casing side wall opposite to said first side wall, said second and third separators each having an outer edge closer to the cylindrical interior casing surface than the radial edges of the rotor bodies.

8. Apparatus as in claim 7 wherein all the vaned 30 pockets in one rotor body are of the same shape and size.

9. Apparatus as in claim 8 wherein all the vanes and pockets in the second rotor body are of the same shape and size on that rotor body.

10. Apparatus as in claim 9 wherein the vanes and pockets on both the first and second rotor bodies are of the same shape and size.
